SNOW SLED

Charles F. Molzen, Wooster, Ohio, assignor to
Rubbermaid Incorporated, Wooster, Ohio

Filed Oct. 1, 1970, Ser. No. 25,294

Term of patent 14 years

Int. Cl. D21—02

U.S. Cl. D34—15

FIG. 1

FIG. 2

FIG. 3

FIG. 4

FIG. 5

FIG. 1 is a perspective view of a snow sled, showing my new design;

FIG. 2 is a top plan view;

FIG. 3 is a side elevational view, the opposite side being substantially a mirror image thereof;

FIG. 4 is a cross-sectional view, taken on line 4-4 in FIG. 3; and

FIG. 5 is a bottom plan view thereof.

I claim:

The ornamental design for a snow sled, as shown and described.
